(57) **CLAIM**

The ornamental design for a television bracket, as shown and described.

DESCRIPTION

FIG. 1 is a rear perspective of a television bracket showing our new design;

FIG. 2 is a front view thereof; and,

FIG. 3 is a side view thereof.

The broken line showing is for illustrative purposes only and forms no part of the claimed design.

1 Claim, 2 Drawing Sheets

FIG. 1

FIG. 2

FIG. 3
